DESIGN.

W. D. TITUS.
LANTERN.

No. 687.

Patented Jan. 9, 1855.

Wes. 687

William D. Titus of Brooklyn, N. Y.
Letters Patent No. 687, Dated Jan'y 9th 1835.

The schedule referred to in these Letters Patent, and making part of the same.

To all whom it may concern.

Be it known that I, W. D. Titus, of Brooklyn, in the County of Kings, and State of New York, have invented and produced a new and original design for a Lantern, and I do hereby declare that the following is a full, and exact description of the same, reference being had to the annexed drawings, making a part of this Specification in which,

Fig. 1. is an external view of a Lantern showing my design.

Fig. 2. is a horizontal section of do. taken at the line (x)(x) Fig. 1.

304

Res. 687

Similar letters of reference, indicate corresponding parts in the two Figs.

The Lantern A, is three-sided or of triangular form and has narrow planes or faces B, which form the junction of the sides. The edges of the sides project a short distance beyond the outer surfaces of the faces B, and form beads (a) leaving the planes or faces somewhat sunken, as clearly shown in Fig. 2.

On each plane or face B, there are two ornamental figures C.C, as clearly shown in Fig. 1. and on the upper part of each side of the Lantern, there is an ornamental Fig.D, also shown in Fig. 1.

I claim the ornamental figures C.C. on the sunken planes or faces B, the beads (a)(a) at the sides or edges of the planes or faces, and the ornamental figures D.D. on the upper parts of the sides of the Lantern, when combined as herein shown to form a new and original design for a Lantern.
